RUDDER TILLER LOCK

Vincenzo Colica, Brooklyn, N. Y.

Application July 19, 1943, Serial No. 495,323

3 Claims. (Cl. 114—162)

This invention relates to new and useful improvements in rudder tiller locks and more particularly to a construction which will permit quick detachability of the usual tiller or operating arm for the rudder.

An important object of the invention is to provide a rudder tiller lock which is especially adapted for use on lifeboats and boats of like capacity and design which in an emergency will permit the application of a tiller to the usual rudder quickly and effectively.

Other objects and advantages of the invention will become apparent to the reader of the following description.

In the drawings:

Figure 1 represents a fragmentary side elevational view showing the tiller lock, tiller and upper portion of a rudder.

Figure 2 is a fragmentary top plan view of the structure shown in Figure 1.

Figure 3 is a side elevational view of the lock.

Figure 4 is a front elevational view of the lock.

Figure 5 is a rear elevational view of the lock with the lock element removed.

Figure 6 is a side elevational view of the lock element.

Referring to the drawings wherein like numerals designate like parts, it can be seen that numeral 5 denotes the shank of a rudder, the upper portion of which is notched at its rear edge as at 6 and is curved in the manner shown in Figure 1 at its forward edge, this latter edge being denoted by numeral 7.

Numerical 8 generally refers to an improved lock for disposition against the curved surface 7.

A tiller is denoted by numeral 9 and has a slot therein for receiving the upper portion of the rudder 5, this tiller having a bulge for disposition in the notch 6 as the tiller fits snugly over the upper portion of the rudder.

The lock 8 consists of an elongated arcuate-shaped plate 10 secured on and adapted to lie flatly against the curved portion 7 of the rudder, the lower portion of this plate 10 having an offset 11 into which the head 12 of a lock element 13 can be disposed when it is desired to remove the tiller 9 from the rudder 5.

The plate 10 has a slotted boss 14 at its rear side through which a pin 15 projecting from the upper end of the lock element 13 is loosely disposed and secured. A strip spring 16 has its free end disposed beyond the boss 14 and bears against the lock element 13 to hold the same in substantially the position shown in Figures 1 and 3 in order to serve as an abutment to prevent rising

of the tiller 9. The lock element 13 is limited in its outward movement in response to the spring 16 by a small cross member 17 secured by a screw or the like 18 to the rear side of the lock element 13.

Obviously, by pushing inwardly on the lock element 13 to overcome the spring 16, the head 12 may be pushed into the offset 11 and the tiller 9 can then easily be removed.

Obviously, the tiller can be slipped down over the upper portion of the rudder 5 as shown in Figure 1 and will simply slide over the lock mechanism without any manual actuation thereof.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In combination, a rudder having a shank, a tiller for the rudder, and means including a quick operative latch for holding the tiller to the rudder shank, said latch being in the form of a spring-projected depressible abutment mounted on an edge of the rudder shank and adapted to abut the top of and prevent removal of the tiller when applied to the rudder shank, said rudder shank having a recess in the opposite edge thereof, said means further including a bulge on the tiller engaged in said recess.

2. In combination, a rudder, a tiller for the rudder, and a quick operative latch for holding the tiller to the rudder, said latch consisting of a plate, the upper portion of the rudder being gradually reduced, said plate being disposed against the reduced portion of the rudder, a spring projected movable member having a head adapted to abut a tiller, said plate having an offset therein for receiving the head when the member is in depressed position.

3. In combination, a rudder, a tiller for the rudder, and a quick operative latch for holding the tiller to the rudder, said latch consisting of a plate, the upper portion of the rudder being gradually reduced, said plate being disposed against the reduced portion of the rudder, a spring projected movable member having a head adapted to abut a tiller, said plate having an offset therein for receiving the head when the member is in depressed position, said member being provided with outwardly movable stop means.
